UNITED STATES PATENT OFFICE.

ROY W. SCHWEIKER, OF LANSDALE, PENNSYLVANIA.

CONVENIENCE OUTLET FOR LIGHTING FIXTURES.

Application filed March 8, 1926. Serial No. 93,291.

This invention relates to "convenience" outlets for lighting fixtures.

It has been proposed heretofore to provide side wall lighting fixtures, for instance, with supplemental, plug-in, outlets to enable current to be taken off for use in connection with a curling iron, electric fan, water heater, or other appliance, such outlets being known as "convenience" outlets. A fixture provided 10 with such an outlet has slots through its base so that the terminals of the plug can be inserted therethrough to make contact with the terminals of an electric outlet located at the back of the base of the fixture.

15 The general purpose of such outlets is to arrange the terminals so that they cannot be touched by the fingers of a person and, at the same time, to suitably insulate them, without interfering with the accessibility of the terminals for plugging-in purposes.

When the convenience outlet is used with a lighting fixture having a porcelain base, this being the kind of fixture with which my invention is particularly adapted for use, due 25 regard must be had to the fact that provision must be made for the flexing or movement of the terminals of the outlet as they require space in which to move; further, the openings for the terminals of the plug must be properly 30 made and arranged so that, in the assembled outlet, the terminals of the plug will be properly guided to the terminals of the outlet and will remain in contact therewith when the plug is in position.

35 Therefore, it becomes necessary to provide an outlet of a construction which will fall within the limitations made necessary by the fact that ceramic material is used in the fixture because in molding and firing a porcelain fixture it is not possible to obtain that degree of accuracy in shape and size which can be had in a metal fixture.

The object of my invention is the provision 45 of a convenience outlet, particularly adapted for use in connection with a lighting fixture of the character set forth and combined with the fixture and the outlet openings in a novel manner, to the end that the terminals of the outlet will be well insulated, not capable of being touched by the fingers of a person, and the outlet will possess durability and permanency, without sacrifice of accessibility; further, to provide an outlet of this character 50 which may be easily applied and wired and wherein the terminals will always be ar-

ranged so that they are in readiness to receive the terminals on the plug and will not be liable to become loosened or twist out of position.

Further objects will appear from the following description of certain embodiments of the invention which are illustrated in the accompanying drawings, in which—

Figure 1 is a front elevation of a side wall lighting fixture provided with the present invention;

Figure 2 is a rear elevation thereof;

Figure 3 is a cross section on the line 3—3 of Figure 5;

Figure 4 is a bottom view of the outlet 70 block;

Figure 5 is a top view thereof;

Figure 6 is a section through the complete outlet, when in position on the fixture;

Figure 7 is a similar view of a modification; 75 and

Figure 8 is a plan view of the insulating block, terminals and wires being absent.

My convenience outlet may be used in connection with any lighting fixture but it is particularly adapted for use on side wall lighting fixtures, especially those which are made of ceramic material, such as porcelain, for instance.

The design of the fixture does not enter into 85 the invention but that design which is illustrated appears in my design Patent No. 71,304, October 19, 1926 and application Serial No. 78,122, filed December 29, 1925.

The base 1 of the fixture has slots 2 through 90 which the terminals of the plug may be inserted.

The outlet itself is secured to the inside of the base 1 as shown in Figure 2 so that it is wholly covered and protected and cannot be 95 touched by the fingers of the user.

I have illustrated two forms or embodiments of the present improvements, said forms appearing, respectively, in Figures 6 and 7, assembled with the fixture whose base 100 appears at 1.

The block 3 is of insulating material and connected to the base 1 by a screw 4 passing through a hole 5 therein and into a nut 6. The nut 6 holds in position on the block 3 a 105 cover which encloses or covers the wires 7, terminals 8, and terminal fastening screws 9.

The cover is of insulating material as shown at 10. Preferably, there is an outer metal plate 11 with which the nut 6 engages. 110

The plate 11 may be omitted and the nut 6 engage with the insulating piece 10.

Referring to Figures 6 and 8, the insulating block 3 is provided with grooves 12 in which lie the wires 7. There are square countersinks 13 which receive and hold the terminals 8 to prevent the latter from twisting. The block 3 is provided with screw threaded holes 14 into which are screwed the screws 9 which pass through openings in the terminals 8 and through loops formed in the ends of the wires 7. Thus the screws 9 serve the double purpose of securing the terminals 8 in the square countersinks 13 and clamping the ends of the wires 7 to said terminals. This will be best understood from Figure 3.

The form of the invention described is shown in Figure 6 in assembled relation to the base 1 of the fixture. The terminals 8 depend below the lower face of the block 3 into cavities 15 which are provided in the inner face of the base 1 to accommodate said terminals and to permit them to be pressed aside when the terminals on the plug are inserted through the slots 2.

It will be observed that with the construction heretofore described, it is unnecessary to mold any projecting parts on the inner face of the base 1 for the purpose of accommodating the outlet, but, on the other hand, the cavities 15 are formed in the fixture when it is molded and fired. With such a construction it is an easy matter to form cavities 15 and slots 2 of the proper dimensions and relationship to fill the offices heretofore specified. Furthermore, the projection of the terminals 8 into the cavities 15 affords additional means for anchoring the outlet on the base of the fixture and to prevent it from twisting.

A rubber or other elastic strip or cushion 16, Figure 6, is located in a groove or channel 17 which extends across the bottom of the block 3; the screw 4 passes through this cushion.

In the form of the invention shown in Figure 7, the block 3 is received within a countersink 18 formed in the base 1 and the chambers or cavities 19 in the block 3 are made of sufficient size to accommodate the terminals 8

and to permit of the flexing or movement of the latter.

I claim:

1. In a convenience outlet for lighting fixtures, the combination with a lighting fixture body which is pierced with narrow slots leading from the exterior to the interior surface thereof, of a block of insulating material carried by the rear wall of said body and wholly covered thereby so as to be unexposed on the exterior of said body, said block having chambers therethrough and provided on one face with countersinks and with channels leading to said countersinks, of terminals received in said countersinks and engaged with the walls thereof whereby said terminals are prevented from twisting or turning, said terminals having contact parts projecting into the chambers and housed by the latter and movable laterally therein, and screws for holding the terminals in the countersinks and for attachment to the ends of the circuit wires, said channels being adapted to receive the circuit wires.

2. In a convenience outlet for lighting fixtures, the combination with a lighting fixture body which is pierced with narrow slots leading from the exterior to the interior surface thereof, of a block of insulating material carried by the rear wall of said body and wholly covered thereby so as to be unexposed on the exterior of said body, said block having chambers therethrough and provided on one face with countersinks and with channels leading to said countersinks, of terminals received in said countersinks and engaged with the walls thereof whereby said terminals are prevented from twisting or turning, said terminals having contact parts projecting into the chambers and housed by the latter and movable laterally therein, screws for holding the terminals in the countersinks and for attachment to the ends of the circuit wires, said channels being adapted to receive the circuit wires, and an insulating cover overlying the block and covering the channels, the chambers, terminals, and screws.

In testimony whereof I affix my signature.
ROY W. SCHWEIKER.
